(57) **CLAIM**

The ornamental design for a travel bag as shown and described.

DESCRIPTION

FIG. 1 is a perspective view of a travel bag showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is top view thereof;

FIG. 7 is bottom view thereof; and,

FIG. 8 is a perspective view thereof in a use condition.

The dot-dash-dot lines represent stitching of the travel bag that forms no part of the claimed design. The remaining dotted lines represent portions of the travel bag that form no part of the claimed design.

1 Claim, 6 Drawing Sheets
